4 Claims. (Cl. 208—68)

This invention relates to a process for the catalytic conversion of hydrocarbons to gasoline and middle distillate fractions. More particularly, the invention relates to a combination cracking process for the thermal and catalytic conversion of hydrocarbons, in order to maximize middle distillate production.

PRIOR ART

The refiner is currently faced with the problem of how best to maximize the production of middle distillates due to the increased demand for jet fuels, stove and heating oils and diesel fuels. This problem exists in those areas where the demand for middle distillates fluctuates with the season and is particularly pertinent to those areas where middle distillate demand exceeds that of fuel oil and gasoline.

The refiner currently maximizes yields of middle distillates by undercutting gasoline and removing all middle distillate stocks from cracking plant feeds. Thus, he operates to the minimum flash point and the maximum pour point on his middle distillate production. At the same time, he conserves his middle distillate production by utilizing the lowest viscosity cutter stocks for blending with residuum to meet the maximum pour point and viscosity specifications on residual fuel oils. Further, he minimizes the use of middle distillates as cutter stock by thermal processing the long residuum in single- or two-coil cracking units or visbreaking units to effect maximum viscosity and pour point reduction on the residuum. Such units generally operate at low pressure and short time-high temperature conditions to crack the heavy waxy gas oils to predominantly low pour point middle distillates with a minimum of gasoline production while obtaining some viscosity reduction on the asphaltic residuum.

These methods have improved the situation, but have not significantly increased the ratio of middle distillate to gasoline production. It would be desirable if a method were available to produce higher ratios of middle distillates to gasoline than presently obtainable.

The increased usage of paraffinic crude oils, for example Middle East and north African crudes, has created a need for an economic processing scheme to produce low pour point residual fuel oils from such crude oils while maintaining a high ratio of middle distillates to gasoline and middle distillates to fuel oil. The increased availability of low sulfur north African crudes enables the refiner to meet the trend towards more stringent sulfur specifications for residual fuel oils. However, such crudes generally contain a higher percentage of straight-run gasoline components and the pour point of the residual fuel is 30° to 50° F. higher than corresponding residual fuel from most Middle East crudes. It would be desirable if a method were available to produce a salable, low pour residual fuel oil while maintaining a high ratio of middle distillates to gasoline and to fuel oil from such paraffinic crude oils.

OBJECTS

In view of the foregoing, it is an object of the present invention to provide a process wherein the ratio of middle distillates to gasoline production is increased to an extent heretofore not possible.

It is a further object of the present invention to provide

2

a process that is more economical and flexible in meeting product demands and qualities than existing processes.

DRAWINGS

5 The invention will be best understood, and further objects and advantages thereof will be apparent from the following description, when read in conjunction with the accompanying drawings, in which:

FIGURE 1 is a graphical representation of the improvement in middle distillate yields obtained by thermal processing in accordance with the process of the present invention;

10 FIGURE 2 is a simplified diagrammatic process flow diagram of a refinery incorporating the process of the 15 present invention.

STATEMENT OF THE INVENTION

The present invention provides an improved process wherein a hydrocarbon feed boiling above 550° F., other than a hydrocrackate boiling above about 550° F., is thermally cracked in a thermal cracking zone to produce synthetic materials, including gasoline and middle distillates, and wherein as the operating temperature is constantly raised, the yields of gasoline and middle distillates increase up to a critical conversion point above which gasoline yield continues to increase in a substantially constant rate but middle distillate yield begins to decrease. In accordance with the present invention the critical conversion point is raised by passing to said thermal cracking zone, along with said hydrocarbon feed, a hydrocrackate boiling above about 550° F. in an amount of at least one volume per ten volumes of said hydrocarbon feed.

20 25 30 35 40 45 50 55 60 65 70

Further, in accordance with the present invention, there is provided, in a process wherein a hydrocarbon feed boiling above 550° F. is thermally cracked in a thermal cracking zone operating at conditions under which 10 to 30 wt. percent of said hydrocarbon feed would be converted to synthetic products boiling below 300° F., in the absence of the hydrocrackate, to produce synthetic materials, including gasoline and middle distillates, and wherein as the operating temperature is constantly raised the yields of gasoline and middle distillates increase up to a critical conversion point above which gasoline yield continues to increase at a substantially constant rate, but middle distillate yield begins to decrease, a method for raising said critical conversion point, which comprises passing to said thermal cracking zone, along with said hydrocarbon feed, a hydrocrackate boiling above about 550° F. in an amount of at least one volume per 10 volumes of said hydrocarbon feed. At least 30 volume percent of the unconverted materials from the thermal cracking zone are converted in a hydrocracking zone to products boiling below about 700° F. and the effluent from said hydrocracking zone, boiling above the end point of said products, at least above 550° F., is passed to said thermal cracking zone.

As used herein, the unconverted bottoms from the hydrocracking zone boils entirely above 550° F. though it may contain a slight amount of lower boiling materials resulting from the incomplete separation of 550° F. end point middle distillates.

By means of the process of the present invention, it is possible to markedly increase the yield of middle distillates per barrel of crude oil and, at the same time, increase the ratio of middle distillates to fuel oil while maintaining constant gasoline production. In addition, residual fuel oils having lower sulfur contents and lower pour points are produced.

PROCESS UNITS AND OPERATING CONDITIONS, GENERAL

70 The process of the present invention includes the combination of a thermal cracking zone and a hydrocracking

zone. The latter may be either a one- or two-stage system with the necessary source of hydrogen. Suitable operating conditions for these two zones are described below.

THERMAL CRACKING ZONE

The thermal cracking zone fresh feed stock may be any of the conventional types such as, for example, a bottoms or residuum fraction obtained from a crude distillation column which boils above about 550° F.

The thermal cracking unit may be a single- or multi-coil unit which operates under conditions of feed rate, temperature, and recycle rate such that 10 to 30 wt. percent of the fresh thermal cracking feed is converted to synthetic materials boiling below 300° F. For example, the thermal cracking unit may comprise a single-coil furnace which converts the residuum feed at a conversion per pass of 4 to 7 volume percent based on the production of 300° F. end point gasoline. Conversion per pass used herein is the ratio of the C₅-300° F. end point gasoline production in barrels per day (b.p.d.) divided by the b.p.d. of total furnace feed (fresh feed plus recycle) and multiplied by 100. Thus, if the C₅-300° F. gasoline production is 1500 b.p.d., the fresh feed to the cracking unit is 10,000 b.p.d. and the recycle is 20,000 b.p.d., the conversion per pass is 5.0 volume percent. Alternatively, the thermal cracker feed may be processed in a two-coil unit wherein the primary or black oil coil operates at low pressures of 50 to 150 p.s.i.g. measured at the coil outlet and a conversion per pass of 1 to 3 volume percent. The secondary or clean oil coil operates on gas oil recycle at pressures of 150-250 p.s.i.g. measured at the coil outlet and a conversion per pass of 5 to 12 volume percent. The effluent from the single- or the multi-coil furnace is passed, after pressure reduction and quenching to a flash separator for the separation of the cracked tar or residuum, and a wide-cut distillate stock. The flash separator operates at a pressure of 25 to 100 p.s.i.g. and a bottoms temperature of 560 to 825° F. The cracked tar from the flash separator is passed, without cooling, to a vacuum stripper where a heavy waxy vacuum gas oil recycle boiling in the range of about 700° to 1000° F. is separated from the cracked tar.

If the thermal cracking zone feed is a vacuum residuum from a two-stage crude unit, and primary coil of the thermal cracking unit operates under visbreaking conditions of 50 to 150 p.s.i.g. pressure at the coil outlet and a conversion per pass of 1 to 3 volume percent.

The coil outlet temperature range is 750° to 950° F. for the primary or black oil coil and 825° to 1025° F. for the secondary or clean oil coil.

To improve operation of both single- and multi-coil thermal cracking units, 1 to 2 wt. percent of water may be injected into the coil inlet tubes of the furnaces to promote short time-high temperature cracking, to reduce coil coking and to give a fuel oil product of higher stability and compatibility.

HYDROCRACKING ZONE

The feed to the hydrocracking zone may be any suitable gas or residual oil such as straight-run gas oil, deasphalted residual oil, thermal cracker gas oil or catalytic cycle oil. In the preferred embodiment of the present invention, the feed to the hydrocracking zone is a thermal gas oil boiling above about 550° F.

Depending on the particular hydrocracking catalyst used, the hydrocracking zone feed may contain relatively large quantities of nitrogen. There is no nitrogen limit on the hydrocracking zone bottoms which are passed to the thermal cracking zone although, under the severe hydrogenation conditions employed, the nitrogen is reduced to very low levels.

It is well known that nitrogen has an extremely deleterious effect upon the hydrocracking performance of acidic hydrocracking catalysts. It is also well known that the nitrogen content of the feed to the hydrocracking zone containing such a catalyst should be kept below about 50

5 p.p.m., preferably below about 10 p.p.m. and, still more preferably, below about 2 p.p.m. of nitrogen. A low level of nitrogen in the feed permits the hydrocracking reaction over an acidic-type catalyst to be conducted at lower temperatures than feeds containing larger amounts of nitrogen compounds.

In cases in which the hydrocracking zone contains an acidic-type catalyst and the feeds are not inherently low in nitrogen, the feed may be hydrofining by conventional methods.

10 In cases in which the hydrocracking zone contains a non-acidic or weakly-acidic catalyst, the nitrogen content of the feed used in the process of the present invention may be relatively high, for example, from 10 to 1000 p.p.m. total nitrogen. Therefore, when the hydrocracking zone contains such catalysts, the hydrofining step may be omitted where the feed contains less than 1000 p.p.m. total nitrogen. It will be noted that non-acidic or weakly-acidic catalysts make excellent hydrofining catalysts. Thus, they 15 can be used in a separate hydrofining stage for the hydrocracking stage containing a non-acidic or weakly-acidic catalyst where the feed contains more than 1000 p.p.m. nitrogen or containing an acid catalyst.

The usual hydrocracking zone operating conditions 20 comprise from about 2000 to 30,000 s.c.f. hydrogen/bbl. of total feed and, preferably, from about 2000 to 15,000, at an LHSV of from about 0.2 to 15 and, preferably, from about 0.4 to about 3.0, at a pressure of at least 1000 p.s.i.g. and, preferably, from about 1000 to 3000 p.s.i.g. 25 and a temperature in the range of from about 400° to 950° F. The preferred initial on-stream temperature is from about 500° to 650° F., with progressive increase to about 750° to 950° F., so as to maintain catalyst activity at a controlled level.

30 The catalyst used in the hydrocracking zone is one wherein a material having a hydrogenating-dehydrogenating activity is deposited or otherwise combined with a cracking component. The cracking component may comprise any one or more non-acidic, weakly-acidic or 35 strongly-acidic materials such as silica, alumina, bauxite, silica-alumina, silica-magnesia, silica-alumina-zirconia, and the like, as well as various acid-treated clays and similar materials. The hydrogenating-dehydrogenating component of the catalyst can be selected from any one or more of the various groups VI and VIII metals, as 40 well as the oxides and sulfides thereof, alone or together with promoters and stabilizers that may have, by themselves, negligible catalytic effect. Examples of suitable hydrogenating-dehydrogenating components are the oxides and sulfides of molybdenum, tungsten, vanadium, 45 chromium and the like, as well as metals such as iron, nickel, cobalt and platinum. More than one hydrogenating-dehydrogenating component may be present and favorable results may be obtained with catalysts containing composites of two or more of the oxides of molybdenum, cobalt, chromium, tungsten and nickel, and with mixtures of said oxides with fluorine. The amount of the 50 hydrogenating-dehydrogenating component can be varied within wide limits from about 0.5 to 30% based on the weight of the entire catalyst.

The proper selection of operating conditions and catalysts should be correlated with the particular type of hydrocracking feed stock used, in order to convert at least 30% of the fresh feed to products boiling below the initial boiling point of the feed. The minimum hydrogen consumption in order to obtain this conversion is 750 s.c.f./bbl. feed. In general, an acidic catalyst such as nickel sulfide and/or cobalt sulfide combined with such acidic materials as a conventional cracking catalyst containing silica-alumina, silica-alumina-zirconia, acid treated clays and the like, is used for hydrocracking the hydrofined light straight-run and catalytic cycle oils; and a non-acidic catalyst, such as a combination of cobalt sulfide and/or nickel sulfide with molybdenum sulfide combined with such non-acidic materials as alumina 55

(preferred), bauxite, silica and zirconia or a weakly-acidic catalyst such as a combination of nickel sulfide and/or molybdenum sulfide with tungsten sulfide, combined with such weakly-acidic materials as silica-magnesia, are used for hydrocracking heavy straight-run and thermal gas oils and deasphalted residual oils.

DESCRIPTION

In order to further illustrate the practice and advantages of the present invention, reference is made to FIGURE 1 which shows a graphic illustration of the yields obtainable by the process of the present invention, compared to the yields obtainable by the conventional thermal cracking of the same feed stocks. The pilot plant data which forms the basis for the solid lines was obtained by thermal cracking a long residuum, boiling above 675° F., from an atmospheric distillation of a 37.1° API north African Libyan crude oil in a single coil pilot plant thermal cracking unit and recycling the vacuum gas oil boiling between 675° and 1000° F. The thermal cracker was operated at a coil outlet temperature of 880° F., a pressure of 250 p.s.i.g., at a fresh feed rate of 1.20 gal./hr. and at a total feed (fresh + recycle) rate of 4.65 gal./hr.

The solid lines show the liquid volume percent yields from the fresh feed to a thermal cracking zone, which include a C₅-300° F. gasoline, a 300° to 675° F. middle distillate and a cracked tar. These results indicate the limiting yields obtainable by conventional thermal cracking and will be referred to herein as Case A.

The dotted lines show the liquid volume percent yields of the same products from the fresh feed to the thermal cracker operating at the same conditions of temperature and pressure as Case A, but with 1.3 volumes of hydrocracker bottoms boiling above 675° F. added per 10 volumes of residuum. These yields were obtained from correlations based on pilot plant data wherein a thermal recycle gas oil similarly obtained was hydrocracked in a once-through single stage hydrocracker over nickel sulfide and tungsten sulfide on silica-alumina at 780° F., 2000 p.s.i.g., and a hydrogen consumption of 1800 s.c.f./bbl. of feed and wherein the unconverted bottoms from the hydrocracker was combined with the residuum to the thermal cracker.

The dotted lines indicate the increased yields obtainable by operating in accordance with the present invention, i.e., adding at least one volume of a substantially hydrogenated bottoms from a hydrocracking zone, operating on a once-through basis, to 10 volumes of fresh thermal cracking zone feed, and will be referred to herein as Case B.

It can be seen from FIGURE 1 that, in both cases, as the thermal cracking zone conversion increases, the yield of C₄-300° F. thermal cracked gasoline increases at a constant rate. The yield of cracked tar, in both cases, decreases with increased conversion until approximately 50% conversion is reached, at which time the yield of cracked tar remains approximately constant with increased conversion. However, in Case B the yield of cracked tar at any conversion is less than in Case A. It will also be observed that, as conversion increases, the yield of 300° to 675° F. middle distillates in both cases increases up to a critical conversion point above which gasoline yield continues to increase at substantially constant rate but middle distillate yield begins to decrease. This critical conversion point is increased from approximately 26, in Case A, to approximately 31, in Case B. The net result, by means of the process of the present invention, is to markedly increase the volumetric yield of middle distillates over the yield obtained by conventional thermal cracking at constant gasoline yield. It must be emphasized that the product yields indicated in FIGURE 1 are obtained from the thermal cracker only and do not include those obtained from the hydrocracker.

In addition, FIGURE 1 indicates that, although the

ratio of middle distillates to gasoline constantly decreases with increased conversion, the ratio at any given conversion point is greater for Case B than Case A. The increase in middle distillates that is obtained in Case B over that obtained in Case A is at the expense of cracked tar and gas.

In a conventional thermal cracker, as conversion increases, the olefinic content of all the products increase, including the gas oil recycle. This increase in olefinic content with an increase in conversion, has a tendency to increase the rate of condensation and polymerization, and also the rate of decomposition to gasoline and gas. Although not intended to be limited to any one theory, or explanation for the results obtained in the process of the present invention, it is believed that the addition of a substantially hydrogenated bottoms tends to slow down the rates of polymerization and decomposition to gasoline and gas. Thus, this makes more material available for conversion into middle distillates.

Referring now to FIGURE 2, there is shown an exemplary over-all process flow diagram suitable for carrying out one or more preferred embodiments of the present invention.

A crude oil charge stock, which may be a single crude oil or a mixture of crude oils, is heated and passed through line 1 to crude column 2. The feed stock in crude column 2 is distilled at substantially atmospheric pressure into a wide-cut distillate overhead, boiling below about 700° F. The overhead is passed through line 3, combined with hydrogen through line 4 and passed into hydrodesulfurizing zone 5. Zone 5 contains a conventional desulfurizing catalyst (such as cobalt-molybdenum on alumina) which saturates the olefins and removes sulfur and a portion of the nitrogen from said overhead. The effluent from zone 5 is condensed in contact with injected condensate water, cooled and passed to a separating drum wherein the condensate water containing the dissolved ammonia and hydrogen sulfide is drawn off and the recycle hydrogen stream is flashed off to return to the hydrogen inlet of zone 5, not shown. The effluent from zone 5 is then passed through line 6 to distillation column 7 for the recovery of products.

The residuum from crude column 2 is removed by line 10 and passed to a thermal cracking zone 11 operating at the above conditions such that 10 to 30 wt. percent of said residuum is converted to synthetic products boiling below 300° F. By way of specific example, the residuum is thermally cracked in a single recycle coil at 250 p.s.i.g., a 5.5 volume percent conversion per pass and 3.5:1 combined feed ratio. (Ratio of fresh feed + recycle to fresh feed.) The effluent from the thermal cracking zone 11 is quenched to a transfer line temperature of about 775° F. and then pressure reduced and passed through line 12 to flash separator 13 operating at 15 p.s.i.g. In zone 13, the effluent is flashed to give a wide-cut distillate fraction boiling below about 700° F. This fraction is passed through line 14, combined with the overhead through line 3, and passed to hydrodesulfurizing, zone 5. The flashed residuum from zone 13 passes through line 15 to vacuum stripper 16 operating at 10 mm. Hg absolute where it is separated into a wide-cut waxy vacuum gas oil of which all or a portion thereof may be recycled through line 17 to the inlet to thermal cracking zone 11. The cracked tar bottoms from the vacuum stripper may be passed through line 18 to product storage as a bunker fuel oil component or to subsequent processing, such as in a solvent deasphalting unit. A portion of the wide-cut vacuum gas oil may be combined with a deasphalted oil, catalytic cycle oil, straight-run gas oil or other suitable gas oil which is passed through line 20, and is passed through line 19 with hydrogen through line 21 to hydrocracking zone 22. Hydrocracking zone 22 operates with a suitable hydrocracking catalyst under conditions as discussed above, in order to convert at least 30% of the feed to products boiling below the initial boiling point of the feed. By way

of a specific example, the vacuum gas oil is hydrocracked in a once-through single-stage hydrocracker over nickel sulfide (6½ wt. percent Ni) and molybdenum sulfide (22 wt. percent Mo) on activated alumina at 650° to 725° F., 2000 p.s.i.g., and a hydrogen consumption of 1100 s.c.f./bbl. of feed. The effluent from the hydrocracking zone after cooling and separation of a hydrogen recycle stream may be passed to any conventional distillation column. In one embodiment of the present invention, this effluent is passed through line 23 and combined with the desulfurized effluent through line 6 to distillation column 7 for recovery of products.

The unconverted materials from hydrocracking zone 22

5 oils to produce a maximum yield of middle distillates using a conventional processing arrangement of two-coil thermal cracking with vacuum flashing the cracked tar, compared with a material balance obtained by processing the same feeds using a processing arrangement in accordance with one embodiment of the present invention, i.e. two-coil thermal cracking with vacuum flashing the cracked tar and single-stage hydrocracking a part of the vacuum gas oil, as described in connection with FIGURE 1. The primary coil of the thermal cracker operates once-through at 750° to 950° and 50 to 150 p.s.i.g. at the coil outlet. The secondary coil operates at 825° to 1025° and 10 250 to 650 p.s.i.g. at the coil outlet.

² Reid Vapor Pressure.

are removed from the bottom of distillation column 7 and at least one volume of hydrocracking zone bottoms is combined with 10 volumes of fresh thermal cracker feed and passed through line 24 to thermal cracking zone 11. The upper limit on the hydrocracker bottom is one volume bottoms per volume of fresh thermal cracker feed. Above this limit there is no further increase in the critical conversion point. Thus, a portion of the bottoms may be removed to line 25 for further processing. Alternatively, the hydrocracker feed rate may be controlled so that all of the hydrocracker bottoms is passed to thermal cracking zone 11.

The total products from the preferred unitary distillation scheme are removed as side cuts from distillation column 7. The propane and lighter boiling materials are removed from the system by line 29. Mixed C₃-C₄'s are removed to product storage by line 30 as LPG. The light straight-run and hydrocracked (C₅-180° F.) gasoline is removed through line 31. The heavy straight-run and hydrocracked (180° to 300° F.) gasoline is passed through line 32 to catalytic reforming zone 33. Catalytic reforming zone 33 may operate under conventional catalytic reforming conditions with a conventional reforming catalyst such as platinum on aluminum. The reformate from reforming zone 33 is passed through line 34, combined with the C₅-180° F. gasoline, and removed to product storage through line 35 as a high octane gasoline. The middle distillates are removed to product storage through line 36. Alternatively, the middle distillate can be split into a 300° to 480° F. kerosene or jet fuel product and a 480° to 675° F. diesel fuel product.

45 Example 2 illustrates processing the same quantity of a 50-50 blend of Middle Eastern and north African crudes, in order to maintain high middle distillates to gasoline ratios and, at the same time, maintain a maximum of 2 weight percent sulfur in the low pour residual fuel oil.

EXAMPLES

Example 1 is a material balance obtained by processing 50,000 b.p.s.d. of north African and Middle East crude

These examples show that, compared with the conventional refining arrangement, the process of the present invention results in a large increase in the middle distillate to fuel oil ratio and the middle distillate to gasoline ratio. Example 2 shows, by blending the two crudes, the refinery is able to maintain these high ratios and meet the 2 weight percent sulfur specification on the low pour fuel oil. 5

Although only specific embodiments of operation of the present invention have been described, numerous variations could be made in those embodiments without departing from the spirit of the invention and all such variations that fall within the scope of the appended claims are intended to be embraced thereby.

What is claimed is:

1. In a process wherein a hydrocarbon residuum feed boiling above about 550° F., other than a hydrocracked fraction as described hereinafter, is thermally cracked in a thermal cracking zone to produce synthetic materials including gasoline and middle distillate, and the effluent thereof is separated into fractions including at least a gasoline fraction, a middle distillate fraction having an end boiling point of at least 550° F., a distillate gas oil fraction boiling above the end boiling point of said middle distillate fraction, and a cracked tar fraction boiling above the end boiling point of said gas oil fraction, and wherein conversion of said feed to said synthetic products increases as operating temperature is raised up to a critical conversion point above which gasoline yield continues to increase as operating temperature is further raised but middle distillate yield begins to decrease; 30

the improvement for raising said critical conversion point to increase the yield of middle distillate and decrease the yield of cracked tar without substantially changing gasoline yield, said yields being with reference to said hydrocarbon feed, which comprises:

catalytically hydrocracking a hydrocarbon oil boiling above about 550° F., separating the oil effluent of the hydrocracking into fractions including middle distillate and a hydrocracked fraction boiling above the end boiling point of said middle distillate fraction separated from the effluent of said thermal cracking zone, and passing at least a portion of said hydrocracked fraction to said thermal cracking zone in an amount of from one to ten volumes per ten volumes of said hydrocarbon feed.

10 2. Process in accordance with claim 1 wherein said thermal cracking zone is operated at conditions under which from 10 to 30 weight percent of said hydrocarbon feed would be converted to synthetic products boiling below 300° F. in the absence of said hydrocracked fraction.

20 3. Process in accordance with claim 1 wherein said hydrocarbon oil which is catalytically hydrocracked comprises a portion of said distillate gas oil fraction separated from the effluent of said thermal cracking zone, another portion of said gas oil fraction being recycled to said thermal cracking zone.

25 4. Process in accordance with claim 3 wherein at least 30 volume percent of said distillate gas oil fraction is catalytically hydrocracked to products boiling below about 700° F.
